UNITED STATES PATENT OFFICE.

AMBROSE F. THOMPSON, OF HUNTER'S HILL, NEW SOUTH WALES.

SEALING-BUCKLE.

SPECIFICATION forming part of Letters Patent No. 678,700, dated July 16, 1901.

Application filed December 4, 1900. Serial No. 38,686. (No model.)

To all whom it may concern:

Be it known that I, AMBROSE FOSS THOMPSON, a subject of the Queen of Great Britain and Ireland, residing at Hunter's Hill, New 5 South Wales, have invented certain new and useful Improvements in Sealing-Buckles for Use on Mail-Bags and the Like, (for which I have applied for Letters Patent of the Colony of Victoria, dated September 28, 1900, No. 10 17,587,) of which the following is a full, clear, and exact description.

This invention relates to improvements in seal-buckles, and refers more particularly to those for use on mail-bags, the object of the 15 invention being to provide a simple, efficient, and reliable buckle for sealing mail-bags so that the strap securing the contents of the bag cannot be unbuckled without breaking the seal.

20 In certain systems in use at present for sealing mail-bags much wax is wasted and time lost in adjusting, and my invention obviates these defects.

A preferred embodiment of my invention 25 comprises, as illustrated in the accompanying drawings, a buckle of ordinary construction underlying a metal bed for sealing-wax, the bed having a flat floor and sides slightly raised so arranged that the buckle cannot be 30 opened without breaking the wax. This bed or receptacle for the wax consists of two parts, one being an extension of the framework of the buckle and integral therewith, the other being movable and hinged to the 35 buckle-frame.

In order that the invention may be clearly understood, reference is made to the accompanying drawings, in which similar letters of reference indicate the same parts in each of 40 the figures.

Figure 1 is a plan of the buckle closed. Fig. 2 is a sectional plan of the buckle open. Fig. 3 is an inverted plan view, showing the reverse side of the buckle to that shown in Fig. 45 1. Fig. 4 is a sectional elevation on line 4-4 in Fig. 2. Fig. 5 is a side elevation with the parts in closed position as in Fig. 1, and Fig. 6 is a side elevation with the parts in the open position as in Figs. 2 and 4.

50 A is the portion of the wax-receptacle which is an integral extension of the buckle-frame. B is hinged portion of the same.

F F are side bars of the buckle, to which B is hinged by means of pin B'.

C is the tongue of the buckle which is attached to the cross-bar C', which is placed below the level of the side bars, as shown. It is to this bar that the strap is sewed. (See Fig. 6.)

G is a catch on the under side of B, which 60 engages and is secured by spring E when the buckle is closed ready for sealing. The spring E is secured to the thickened portion or cross-bar A' of the fixed part A, and said bar A' and the adjacent portion of the bottom a terminate short of the flange a' of part A to provide an opening A², (see Figs. 2 and 3,) whereby to accommodate the catch G and permit the latter to engage the spring E. The object of this catch is to prevent the 70 hinged plate B being accidentally forced open and the seal thus destroyed. The spring E is provided with a button D, by means of which the catch is released when it is desired to break the seal and open the buckle. 75 The fixed part A is slotted, as at a², to permit a sliding movement of button D and the end of the spring E.

The method of using my invention is as follows: When the buckle is closed, (i. e., 80 when the free end of the tongue is resting on the cross-bar, as shown in Fig. 2,) the hinged piece B is lowered into the position shown in Fig. 1. The melted wax is then poured into its receptacle and the seal impressed thereon. When it is desired to break the seal and open the buckle, the button D is pressed back and the catch G thus released from contact with the spring E. It is then a very 85 easy matter to prize up the hinged piece B, 90 and thus release the tongue of the buckle.

Having now particularly described and ascertained the nature of my said invention and in what manner the same is to be performed, I declare that what I claim is—

1. A buckle, comprising a frame, a depressed portion forming a bed for wax, and a movable tongue lying in close proximity to the said bed when in the closed position and movable through the plane of the wax-bed 95 in closing and opening, as and for the purpose specified.

2. In a sealed buckle the combination with a buckle consisting of a tongue and cross-

bars, of a wax-bed consisting of a fixed and a hinged part substantially as described and as illustrated.

3. A buckle for use on mail-bags and for other purposes, comprising a buckle frame and tongue, and a bed for receiving a sealing substance, said bed including two parts, one movable relatively to the other, one of said parts having a catch member and the

other a spring for engaging the catch member.

Signed at Sydney, New South Wales, this 5th day of October, 1900, in the presence of two witnesses.

AMBROSE F. THOMPSON.
